UNITED STATES PATENT OFFICE.

LEON E. LA BOMBARD AND MELVIN H. SIDEBOOTHAM, OF CHELSEA, MASSACHUSETTS,
ASSIGNORS TO SPECIALTY AUTOMATIC MACHINE COMPANY, OF CHELSEA, MASSA-
CHUSETTS, A CORPORATION OF MASSACHUSETTS.

GLUER.

Application filed April 6, 1921. Serial No. 459,135.

To all whom it may concern:

Be it known that we, LEON E. LA BOMBARD and MELVIN H. SIDEBOOTHAM, citizens of the United States, and residents of Chelsea, in the county of Suffolk and State of Massachusetts, have invented certain new and useful Improvements in Gluers, of which the following is a specification.

This invention relates to means for applying an adhesive, hereinafter referred to generically as glue, to sheet material; the present invention being particularly designed for use in box folding machines wherein blanks are successively passed over a narrow wheel or disk and take a stripe of glue from said disk.

In the use of devices or appliances of this character, dust or fibers carried by the blanks tend to accumulate on the periphery 20 of the disk and soon clog thereon and interfere with the transmission of a correct stripe of glue to the passing blanks. A "doctor" device in the form of a scraper does not prevent accumulation of dust or fibers on the disk because there must be sufficient space between the two to permit the disk to carry a film of glue past said device.

The principal object of our present invention is to provide a gluer in which it is impossible for dust or fibers to so accumulate on the rotary disk as to clog the latter and interfere with the operation of the box-folding or other machines of which the gluer forms a part.

With the above-stated object in view and other objects incidental thereto, as will be explained hereinafter, the invention consists in the construction and combination of parts substantially as hereinafter described and 40 claimed:

Of the accompanying drawings:

Figure 1 is a perspective view, partly broken out of a gluing appliance constructed according to our invention.

Figure 2 is a plan view.

Figure 3 is a detail vertical sectional view on line 3-3 of Figure 2, on a smaller scale.

Figure 4 is a sectional elevation on line 4-4 of Figure 2.

Figure 5 is a detail sectional elevation on line 5-5 of Figure 2.

The glue pot or box may be of any suitable construction so far as the present invention is concerned. As illustrated it in-

cludes four wall portions 12, 13, 14 and 15, 55 an intermediate wall or web 16, and a cover, a portion of which is shown at 17.

Mounted in a bearing 18 carried by the web 16 is a shaft 19 carrying the glue-applying wheel or disk 20 at the end within 60 the glue-holding portion of the pot, and having a pinion 21 at its other end. Meshing with the pinion 21 is a pinion 22 mounted on a stud shaft projecting from the web 16. Meshing with the pinion 22 is a pinion 23 65 carried by a suitable drive shaft not necessary to illustrate.

Referring to Figure 3 in connection with Figure 1, a shaft 24 is mounted in an eccentric sleeve 25 which latter is mounted to 70 be rotatively adjusted in a bearing 26 projecting from the web 16. As indicated by comparing Figures 3 and 4, the internal bore of sleeve 25 is eccentric to the bearing 26 for a purpose presently explained.

Integral with or secured to the inner end of the shaft 24 is a grooved doctor roll 27. The walls of the groove in said doctor diverge and straddle the peripheral portion of the glue disk 20. In other words, the groove in the doctor is wider at its mouth than at its bottom. At its bottom the width of the groove is practically the same as the thickness of the edge of the disk 20, the purpose of which will be presently explained.

Carried by the outer end of the shaft 24 is a pinion 28 which meshes with the pinion 22 so that said pinion 22 drives the pinions 21 and 28, and consequently the disk 20 and doctor 27, in the same direction as indicated by the arrows in Figure 1. The proportions of the train of gearing described is such, as shown, that the doctor rotates considerably faster than the glue disk. The thickness of the film of glue which is permitted to be carried up on the periphery of the disk to applying position is controlled by the space between the bottom of the groove in the doctor and said periphery.

A difficulty experienced with many prior types of devices employing narrow glue wheels or disks which, as in box-folding machines, are required to rotate very rapidly, is that they are liable to carry sufficient excess of glue on the sides of the disks to result in centrifugal force carrying some of the excess out onto the periphery, result-

ing in too much glue being applied to the passing blanks. By the employment of our improved rotary doctor which acts in a direction to have what can be properly explained as a downward wiping or sweeping action, excess of glue is thrown back into the pot. Owing to the flaring shape of the groove in the doctor there is no objectionable friction between the oppositely moving 10 surfaces of the disk and grooved doctor. The width of the bottom of the groove so closely approximates the thickness of the edge of the disk that it is impossible for the edges or corners of the periphery of the 15 disk to carry too much glue to applying position.

It is, of course, desirable that the doctor shall be capable of adjustment toward, or 20 from the glue disk without interfering with the connections or means for rotating them. For this purpose the eccentric sleeve 25 has an arm 29 extending up through a recess or slot in the bearing 26, and by means of said arm the sleeve can be adjusted rotatively 25 so that, since its bore forms the bearing for shaft 24, the said shaft and the rotary doctor can be very accurately and finely adjusted relatively to the periphery of the disk.

30 To effect and maintain the adjustment of the arm 29 of the eccentric sleeve, we provide a screw 30 mounted in a lug 31 rising from a plate 32 mounted on the cover of the box. The inner end of the screw bears 35 against a lug 33 projecting laterally from the upper end of the arm 29. Between the other side of the lug 33 and a socketed screw 34 mounted in another lug 35 of the plate 32 is a spring 36 acting to yieldingly hold 40 the lug 33 in contact with the adjusting screw 30.

To enable the rotary doctor to attain its best efficiency, it is desirable to keep it clear 45 of excess of glue. To this end we employ a clearer 37 which is shaped to conform closely to the groove in the doctor and to the periphery thereof. As illustrated, portions of the clearer also extend in close to the outer sides of the doctor. The clearer 50 is mounted so that its relationship to the doctor remains constant regardless of adjustments of the doctor. To this end the clearer is mounted on a block 38 formed as a part of a clamp ring 39 which is mounted 55 on and secured to the inner end of the eccentric sleeve 25 (Figures 1, 2 and 3) by a clamp screw 40.

When a gluer device is left inoperative 60 for some time, as over night, glue dries on the exposed portion of its periphery. Sometimes a piece of a blank is stuck thereon. For these and other reasons it is desirable to remove from the disk any undesirable accumulation so that none will be carried 65 around to the doctor. For this purpose we

employ a clearer to act on that portion of the periphery of the disk passing from upper or applying position down toward the glue. Said clearer, in the specific form illustrated, comprises a scraper 41 which is 70 secured at its lower end (Fig. 5) to the wall 12 of the box by any suitable means such as a screw 42. An upper screw 43 (Figs. 1 and 3) tapped through said wall and bearing against the upper portion of 75 the scraper may be employed to vary the pressure of the tip of the scraper against the disk.

An important function of the clearer or 80 scraper 41 is that it removes from the disk 20 any foreign substance which might otherwise be carried down into the glue and then be carried on by the disk so as to interfere with the proper action of the doctor or be carried on to the passing blanks. It is located at a distance from the point where the disk applies glue to the box blanks or other material fed over the disk; therefore, if there is any dirt, or dried glue, or pieces 85 of blanks, adhering to the disk, such foreign matter is removed. Consequently the periphery of the disk is cleaned after leaving applying position, so that it will carry 90 a clean supply of glue first to the doctor 27 and then to the point where said glue is applied to the passing blanks. 95

As is well-known, every gluer of the type referred to herein is so constructed that a peripheral portion of the glue disk or roll is exposed for the free passage of the sheet material or blanks in a plane tangential to such peripheral portion. And to permit such passage there must be no obstruction located in the path of travel of the sheet material or blanks. Therefore, in the present structure, both the doctor 27 and the clearer or scraper 41 are below the plane of the top of the glue disk 20 so that the blanks can pass freely along said plane to receive stripes of glue the full length of the glue laps of the blanks. 100

105 While the member 20 is illustrated as a disk, we do not limit ourselves thereto since its axial dimension may be such as to render the term roll more aptly descriptive. 110

115 Having now described our invention, we claim:

1. In mechanism of the character described, a glue receptacle; a disk mounted to rotate therein, and a rotary doctor in proximity to the disk, portions of said doctor extending in close proximity to the sides of the disk. 120

2. In mechanism of the character described, a glue receptacle; a glue carrier mounted to rotate therein and having a portion of its periphery exposed for the passage of sheet material in contact therewith, a rotary doctor in proximity to the carrier; means being provided for rotat- 125 130

- ing the carrier and doctor in the same direction.
3. In mechanism of the character described, a glue receptacle, a glue carrier mounted to rotate therein and having a portion of its periphery exposed for the passage of sheet material in contact therewith, a rotary doctor in proximity to the carrier, and a clearer close to the rotary doctor to remove glue therefrom. 60
4. In mechanism of the character described, a glue receptacle, a glue carrier mounted to rotate therein, a doctor in position to control the film transferred by the carrier from the glue to applying position, and a scraper in position to act on that portion of the carrier traveling from applying position to the glue. 65
5. In mechanism of the character described, a glue receptacle, a glue carrier, a doctor in proximity to one portion of the carrier, a scraper close to another portion of the carrier, and means for rotating the carrier in a direction to cause its periphery to travel from the glue past the doctor, then to applying position, and then past the scraper to the glue. 70
6. In mechanism of the character described, a glue receptacle, a rotary glue carrier having a portion of its periphery exposed for the passage of sheet material in contact therewith, a doctor for the carrier, and means for removing glue from the doctor. 75
- 35 7. In mechanism of the character described, a glue receptacle, a rotary glue carrier, a doctor for the carrier, means for removing glue from the doctor, and independent means for removing glue from that portion of the carrier moving from applying position to the glue. 80
- 45 8. In mechanism of the character described, a glue receptacle, a disk mounted to rotate therein, a rotary doctor in proximity to the disk, means for rotating the disk and doctor in the same direction, and means for adjusting the rotary doctor relatively to the disk. 85
- 50 9. In mechanism of the character described, a glue receptacle, a carrier mounted to rotate therein, a rotary doctor in proximity to the carrier, a clearer for the doctor, and means for adjusting the doctor and clearer without disturbing their co-relation- 90
- 55 ship. 95
10. In mechanism of the character described, a glue receptacle, a carrier mounted to rotate therein, an adjustable member, and a doctor and a clearer for the doctor both carried by said adjustable member. 100
11. In mechanism of the character described, a glue receptacle, a carrier mounted to rotate therein, and a peripherally grooved rotary doctor in proximity to the carrier. 105
12. In mechanism of the character described, a glue receptacle, a carrier mounted to rotate therein, and a peripherally grooved rotary doctor in proximity to the carrier, the groove in the doctor being wider at its mouth than at its bottom. 110
13. In mechanism of the character described, a glue receptacle, a carrier mounted to rotate therein, a peripherally grooved rotary doctor in proximity to the carrier, and a clearer extending into the groove of the doctor. 115
14. In mechanism of the character described, a glue receptacle, a disk mounted to rotate therein, a peripherally grooved rotary doctor in proximity to the disk at one side of the axis of the latter, a scraper close to the disk at the other side of the axis of said disk, and a clearer for the rotary doctor. 120
15. In mechanism of the character described, a glue receptacle, a rotary glue carrier, a doctor for the carrier, and a clearer independent of the doctor and at a distance from the point where the carrier applies glue to material fed past it, said doctor and clearer being located out of the plane of a line tangential to the periphery of the glue carrier to permit said material to receive a stripe of glue while travelling in a straight path. 125
16. In mechanism of the character described, a glue receptacle, a rotary glue carrier, a rotary doctor for the carrier, and a scraper located at a distance from the point where the carrier applies glue to material fed past it, said doctor and scraper being below the plane of the top of the glue carrier to permit said material to receive a stripe of glue while travelling in a straight path. 130

In testimony whereof we have affixed our signatures.
